W. L. Williams,

Bundling Wood.

N° 28, 243.

Patented May 8, 1860.

W. L. Williams

UNITED STATES PATENT OFFICE.

WM. L. WILLIAMS, OF NEW YORK, N. Y., ASSIGNOR TO HIMSELF AND THO. J. O'CONNOR,
OF SAME PLACE.

MACHINE FOR BUNDLING WOOD.

Specification of Letters Patent No. 28,243, dated May 8, 1860.

To all whom it may concern:

Be it known that I, WILLIAM L. WILLIAMS, of the city and State of New York, have invented, made, and applied to use certain new and useful Improvements in Means for Bundling Kindling Wood; and I do hereby declare that the following is a full, clear, and exact description of the construction and operation of my said invention, reference 10 being had to the annexed drawing, making part of this specification, wherein—

Figure 1, is a plan of my said machine. Fig. 2, is a vertical section of the same, and Fig. 3, is a side elevation of the jaw for holding and twisting the wire.

Similar marks of reference indicate the same parts.

My present invention relates to parts that I have improved and perfected for operation 20 in machines for bundling kindling wood, and they become improvements upon the machines for which I have heretofore obtained Letters Patent, one under date of November 15th 1859, and the other under date of August 16th 1859.

I apply a series of holding clamps to prevent the wood falling over as the bundle is separated from the mass of wood in the trough. I also use feeding and sustaining 30 slides that give motion to the wood, and also aid in forming the bundle and keeping the wood in a proper upright position. The wire that is passed around the wood is held in a peculiar jaw and twisted until the bundle is 35 tightly secured.

In the drawing *a*, is a trough in which the kindling wood is placed by hand, or passed from the splitting machine; *b*, is a slide that is actuated by hand or any convenient mechanism that coming up behind the wood 40 forces the same along in the trough and against the curved end of the trough (at *c*) so as to place the wood in position for forming a bundle, and one bundle is shown 45 at *d* as separated and raised up by means of a follower (*e*) the same as shown in my patent of November 15th 1859 on which this is an improvement.

In order to prevent the end pieces of wood 50 falling down as the mass is forced along, I employ the slide *f* that is made with a semi-circular end corresponding with the diameter of the bundle of wood. This slide *f* is projected by means of the arm *g* on the 55 shaft *h*, on which a spring *i* acts, so that so

soon as the follower *e*, descends sufficiently, the spring *i* throws the slide out against the end of the mass of wood, and said spring yielding on the wood being pressed forward, allows the slide to move back, and in order 60 to insure the entire retraction of said slide so that the follower in rising will not take the same, I give a partial revolution to the shaft *h*, at the proper time in the direction of the arrow, by hand or suitable automatic mechanism, and draw the slide *f* entirely back.

The kindling wood has been kept from falling over by a straight clamp acting on the ends thereof, but where a circular 70 bundle is separated from the mass, the pieces near the edge of the trough would not be held up by said straight clamp, I therefore make use of a series of spring holding clamps *k*, *k*, set on a fulcrum 1, and 75 pressed to the ends of the wood by the springs 2, 2, and by the curved form given to the ends of this series of clamps, the wood is sustained all around the place from which a bundle has been taken.

l, is a jaw for twisting the wire somewhat similar to that in my aforesaid patent, the jaws being closed by a sliding conical ring 3 actuated by hand or otherwise. My improved jaw is however shown at *m*, Figs. 85 1 and 3. The same is formed by a shaft (*m*) having jaws 4, 4, at the end, to receive the wire as represented by red lines.

5, is a follower set to slide in a groove in *m*, and having a block 6, near the end 90 thereof; the operator passes a wire around the bundle and draws the ends into the jaws 4, he then slides up the follower 5, the block 6, of which fills the jaws and holds the wire firmly while the shaft *m* is revolved 95 sufficiently to twist and tighten the wire around the bundle of wood. The shaft *m*, and jaws may be revolved by hand or by mechanism applied to the wheel 7.

In cases where the wood has been sufficiently consolidated into a bundle (by the band *o*, or otherwise) I find it preferable not to pull on the wire to tighten the bundle as the jaw 4, revolves and crosses the wire (shown by red lines) as set forth in my 105 aforesaid patent of Nov. 15, 1859, because the bundle being solid is apt to cause the wire to break, I therefore introduce a jaw or jaws *r*, shown in plan Fig. 4, and in elevation Fig. 5, the same setting as closely to 110

the wood as convenient and the wire is led through this jaw *r*, before being passed to the jaw *4*, so that on revolving the said jaw *4*, the twisting of the wire commences at the 5 bundle of wood and unnecessary strain on the said wire in pulling the bundle tight is avoided.

The jaw *r*, may be formed in the diverging manner shown, so that the wires will come 10 near each other by being drawn down into the same, but if more convenient the sides of this jaw might be moved back and forth by suitable mechanism so as to bring the parts of the wire near to each other before 15 twisting.

In order to compress the bundle of kindling wood (after it has been separated from the mass by the follower *e*, or otherwise) I make use of an expansive band or 20 wire *o*, one end of which is attached to the machine, the other end to a lever *p*. The natural expansion of this band when unacted on, or a spring applied to the lever *p*, causes said band to assume a sufficiently 25 large diameter to allow the bundle of wood *d*, to be passed thereinto, when upon drawing said band by the lever *p*, or otherwise it compresses and effectually packs the bundle into a tight mass. Two of these 30 bands might surround the bundle and be pulled upon in opposite directions.

By reference to my aforesaid patents it will be apparent how the present improvements thereon could be applied and operated 35 either by the use of automatic machinery, or be moved by hand power applied to any or all of the parts, for which reasons the representation of automatic machinery, or of the parts shown in my aforesaid 40 patents is rendered unnecessary.

What I claim and desire to secure by Letters Patent, is—

1. A series of clamps *h*, acting on the ends of the split kindling wood contiguous to the place from which the bundle is removed for holding up the mass of wood as set forth. 45

2. I claim the sliding follower *b*, in the trough *a*, for moving the wood along in said trough and conveying it into the bunting apparatus, as specified. 50

3. I claim the yielding semi circular supporting slides *f*, taking the sides of the pieces of kindling wood as they stand in the trough *a*, and assisting in gathering 55 them into a bundle and at the same time preventing them from falling down as pressed along in the trough as set forth.

4. I claim the revolving jaw *4*, and sliding blocking piece *6*, for receiving, holding, 60 and twisting the wire as specified.

5. I claim the jaw or jaws *r*, between the bundle of kindling wood and the apparatus for twisting the wire, the same acting to confine the wire near the bundle while 65 being twisted, as and for the purposes set forth.

6. I claim one or more expansive ring bands or wires applied to compress the wood into a compact bundle by drawing 70 upon and tightening the said band or wire for the purposes and as set forth.

In witness whereof I have hereunto set my signature this thirty first day of March 1860.

W. L. WILLIAMS.
